WINDING MACHINE

Howard E. Swift and Edward R. Davis, Westfield,
Mass., assignors to Foster Machine Company,
Westfield, Mass., a corporation of Massachusetts

Application June 2, 1942, Serial No. 445,430

19 Claims.

(Cl. 242—43)

This invention relates to new and useful improvements in winding machines and more particularly to a machine adapted for the purpose of winding packages of so-called "pineapple" shape, that is with tapered ends, the degree of taper at either or both ends being selective.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate modifications of the invention, and, together with the description, serve to explain the principles of the invention.

Of the drawings:

Figure 1 is a fragmentary front elevation of the present invention as applied to a winding machine of standard construction;

Figure 2 is a right end elevation of Figure 1;

Figure 3 is a plan view of the winding mechanism shown in Figure 1 with certain parts omitted showing the winder at the beginning of its operation;

Figure 4 is a plan view corresponding to Figure 3 but showing the package nearly filled;

Figure 5 is a plan view of the winding mechanism with certain parts omitted, to show the mechanism in position to maintain a constant length of yarn guide traverse and a full wound package produced therewith;

Figure 6 is another plan view of the winding mechanism with certain parts omitted, showing the winder at the beginning of its operation, and with some parts changed from those shown in Figure 3 to show the mechanism in position to move some parts through a greater amplitude than shown in Figure 3;

Figure 7 is a plan view similar to Figure 6 but with the winder shown in full package position;

Figures 8 and 9 are fragmentary detailed side and front elevations of the yarn guide; and

Figures 10 and 11 are fragmentary detailed front and side elevations of a modified form of the interconnecting studs assembled on their guide bar.

For convenience "yarn" is hereafter used to mean thread, yarn or other filamentary material.

Among the more specific objects of the present invention are the provision of:

5 A novel and improved apparatus particularly adapted for the rapid and accurate winding of yarn into a package which may be either tapered or square at one or both ends, and which apparatus may be applied for that purpose to known types of winding machines;

Means for controlling the traverse of the yarn 10 guide from its driving means so that the relative extent of movement of the driving means and of the guide may be subjected to controlled variation as by the attained diameter of the package;

15 Means co-related with the foregoing to give the yarn guide a traversing movement either less than, equal to or greater than that of the primary traversing mechanism;

Positive control means for the formation of the 20 package ends to predetermined shapes, such means being easily and simply attached;

Improved means for attaching, lubricating and otherwise servicing the apparatus;

25 A dependable, easily manufactured, light, inexpensive mechanism for the purpose intended.

In accordance with the illustrative embodiment of the present invention, means are provided for positively rotating the core at a relatively high speed while it is supported on a driven spindle, 30 and this spindle is preferably located near the top of the machine frame where it is easily accessible. Geared to the spindle and driven therewith are cam means for reciprocating a traverse member at a relatively constant velocity, and 35 this member is supported on a pivotally or swingably mounted frame so that it may move from the package as the package builds up through the winding of yarn on the core.

40 A yarn guide is reciprocably carried by the pivoted or swinging frame and is moved back and forth at a relatively constant distance close to the surface of the package or even against the surface of the package, the distance being maintained in the illustrative embodiment by means 45 of a roller or other member mounted on the frame, bearing against the surface of the package and supported between the package and the yarn guide.

Means are provided for interconnecting the 50 cam driven reciprocating member and the yarn guide so that the yarn guide is driven from the cam, and as embodied the reciprocating member or guide-tubing moves an inclined cam member or primary guide a fixed distance along a fixed track, at a definite synchronous relation to the

winding speed, while an oppositely inclined cam member or secondary guide takes its motion from the primary guide through a movable coupling, which coupling is given a motion which is the resultant of the motion of the primary guide and of a tertiary guide, said tertiary guide in turn being moved or positioned according to certain factors hereafter described. The secondary guide carries the yarn guide through which the yarn is actually delivered to the surface of the package; thus the package build-up results from a complex of controlled conditions. In this connection the word "fixed" unless otherwise qualified means fixed within the system of parts carried by the swinging frame, and such terms as "vertical" and "horizontal" are used in a general sense rather than with strict accuracy. The various parts called vertical or horizontal will obviously move several degrees out of true position as the swinging frame tilts according to the build-up of the package.

The factors determining the action of the tertiary guide are the thickness which the package has attained, this being reflected in the distance of the swinging frame from the immovable bed frame of the machine, and the connections made between the bed frame and the tertiary guide, which modify a certain swing of the tertiary guide about a pivot transverse to the direction of movement of the primary guide.

The foregoing general description and the following detailed description of a preferred embodiment of the invention are by way of explanation of the preferred embodiment herein selected for purposes of illustration, but are not restrictive thereof.

Referring now particularly to the various figures of the drawings, the improved winding mechanism of the present invention is shown as applied to a standard winding machine generally known in the trade as the "Foster precise winder." The mechanism of the present invention is carried in the usual manner at the top of a main frame 1, which carries lower down a cam shaft 2 driven by suitable mechanism 3. A cam 4 on the cam shaft imparts reciprocating traverse motion to sleeve 5 through suitable connections such as a roller stud 6. The sleeve 5, which slides on a guide rod 7, terminates at its outer end in an upstanding finger 5A to which the primary guide 17 is directly connected. The apparatus of the present invention is supported on a guideway 8 by an arm 8A pivoted about the cam shaft 2, by which arrangement the entire traverse system rocks outward as the package P builds up.

As best seen in Figure 2, the guideway 8 is composed generally of a frame 8B to which a front plate 8C and a base plate 13 are suitably secured, the latter conveniently held by upright studs 15 near each end. Other upright studs 16 further out hold blocks 24 to which an elevated beaded cover 25 is secured by screws 24A. The cover is downwardly flanged to fit over a corresponding upward edge flange of the base plate, and is beaded as at 25A and 25B to guide the yarn Y, both beads of the cover directing the yarn to the yarn guide 32 above contact with the cover face, and hence away from oil or dust thereon. A felt strip 26 riveted to the underside of the cover over the locus of the tertiary guide can be oiled through appropriate holes 27 in the cover, thus providing means for lubricating the guide parts without danger of getting oil on the yarn. Before describing the guide mechanism in

detail, it will be mentioned that the entire tilting assembly follows the face of the cone by the power of an adjustable tension spring 100 suitably attached at its respective ends to the stationary main frame 1 and the swinging frame 8, and contact with the cone face is made by a long pressure roll 101 with bearings at either end in a yoke 104 about as long as the front plate 8C, and pivoted as at 105 to a bracket 106 on the outer face of such plate with a stop plate 107 above and a collar and spring 108 or other suitable arrangement to give some resilience. An adjustable stop screw 56 bracketed to the main frame 1 limits the outward movement of the swinging traverse system.

The guide mechanism in detail comprises the three guides mentioned in the general description and their associated parts. Immediately on top of the base plate 13 there is a guide yoke 10 carrying the tertiary guide bar 18 and pivoted at mid length on the base plate by a vertical stud 12. An arm 30 or 30A rigid with the yoke extends to the left outside the guideway, as seen in Figures 3, 4, 6 and 7, and a link 29 connects the outer end of such arm with an anchorage 28 on the fixed frame 1, the effect being that at the beginning of the wind, as in Figure 6, the end of the bar 18 opposite the base of the package is farthest from the package but during the building up motion, as the winder tilts further out, the arm being held by the link causes the yoke 10 and bar 18 to gradually assume the opposite inclination, as in Figure 7.

The ends of the yoke 10 are upstanding and hold the bar 18 high enough off the base of the yoke to leave clearance for movement of the primary guide 17, which is a horizontal plate at the top of finger 5A, all as shown in Figure 2. This plate 17 is slotted at an angle (about 50° in the illustrative embodiment) leftward. The secondary guide 21 is another flat plate parallel to plate 17 but above the bar 18, slidable on the rod 22, and slotted oppositely to the slot in plate 17. A finger 21A rigid with the plate 21 projects towards the package, carrying the yarn-laying guide 32. A connecting element or runner block 19 which slides on the bar 18 and with that bar constitutes the tertiary guide, engages by top and bottom studs 20 and 20A with the slots in the primary and secondary guides respectively. From the above it will be observed the amplitude of end-to-end travel of the yarn-guide 32 may or may not be the same as that of the primary guide 17, according to the position of tertiary guide bar 18; this is apparent from a comparison of Figures 3, 4, 5, 6 and 7.

Figure 10 shows an end elevation of the top and bottom studs 20, 20A in block 19 while Figure 11 shows a side elevation of a modified form in which the studs 20 and 20A are offset with reference to each other, stud 20 being further from the tertiary guide bar 18 than stud 20A. With the bottom stud 20A retained in its location and with the top stud 20 located further away from the tertiary guide bar 18, as the bar 18 is inclined in either direction, the block 19 also is inclined which moves the top stud 20 further around and thereby moves the secondary guide further along in its travel.

In Figure 6 the first turn of yarn Y' is being laid on a bare core C. The primary guide 17 is at its extreme left position and the bar 18 is at its extreme outer position due to the swinging frame 8 being all the way in, with roller 101 against the empty core. While the primary guide

17 has carried the block 19 with it to the left, the bar 18 has also carried the block far out with respect to the slot in 17, and thus also far out with respect to the slot in the secondary guide 21. As a result, 21 is at its extreme left position along its guide rod 22, and thus the yarn guide finger 21A, with the yarn guide 32, is at the position to start the first layer of the package. This layer is guided to its top turn Y2 by movement of the primary guide 17 imparted by cam 4, transmitted to the secondary guide 21 through block 19 and its studs. The slant of the bar 18 brings the block towards the bottoms of the intersecting slots, and thus pushes the secondary guide 21 to the right beyond the travel of the primary guide, just as it was to the left beyond the travel of the primary guide at the beginning of the stroke. All this is shown in dotted lines at the right of Figure 6. Thus at the beginning of the wind the secondary guide travels through a greater amplitude than the constant path of reciprocation of the primary guide.

Gradually, as the package builds up, the difference diminishes until the final condition shown in Figure 7 obtains at the winding of the outermost layer. Here the travel of the secondary guide is less than that of the primary guide because at the base turn Y3 the studs on the block 19 are close to the bottoms of their respective slots and at the top turn Y4, as shown in dotted lines, they are close to the tops of the slots. By varying the speed with which the angle of tertiary guide bar 18 changes, the taper of the base and of the top of the cone can be changed. This can be done by substituting a different length of arm such as 30A for 30, changing the length of link 29, and by other appropriate mechanical arrangements. The farther the bar 18 varies from parallelism to the face of the package, the longer and gentler the shoulder slope will be. The ultimate of the converse of this proposition is that if the bar 18 is always parallel to the face of the package the shoulders will be perpendicular to that face. Such a wind can be accomplished by the arrangement shown in Figure 5, where the link 29 is disconnected, and a clamp screw 11B set in the middle of a swing limit slot 11A, thus permanently clamping the yoke 10 so that the bar 18 is always parallel to the face of the package, being unaffected by the tilt of the arm 8A. Here as the block 19 is reciprocated by the primary guide 17 it cannot travel either in or out in the slot, and thus the relation of the secondary guide to the primary guide remains constant, with the result that every layer of yarn on the cone is the same length. Since the package face is conical, this actually gives a slight concave conicity to the top and a convex conicity to the base. The solid and dotted positions of the guide in Figure 5 are not the extreme positions.

Similarly, the bar 18 may be held in positions non-parallel to the face of the package by disconnecting link 29 and clamping screw 11B in the desired position in its slot 11A. With the bar 18 held in the position shown in Figure 6 and with link 29 disconnected, the maximum yarn traverse will be obtained, and shorter traverses may be obtained by moving the bar counterclockwise until it is in the position shown in Figure 7. When held in that position, the minimum traverse will be obtained, the yarn traverse for each position of the bar 18 remaining constant during the whole process of winding as the bar 18 is held in a fixed position. Intermediate positions of

the bar 18 will produce yarn traverses of intermediate length.

The secondary guide 21 is upturned as at 21A, Figure 2, so that the thread guide 32 can deliver the yarn tangent to the bearing roll 101 and close to the bite of that roll on the package face, thus avoiding whipping and backlash, particularly at the ends of the laying traverse. The yarn may be kept from jumping out of its guide by a split sleeve guard, or an incomplete wire loop guard such as 31, surrounding the yarn guide, so that only when turned to bring the opening in the guard opposite the opening in the yarn guide can the yarn be lifted in or out.

15 It will be apparent from the foregoing that a variety of shoulder forms may be obtained by appropriate variations of the relatively moving parts, as by changing the pivot point of the guide yoke 10 or by substituting guide plates slotted in patterns other than those shown, for either or both the guides 17 and 21.

20 It will also be understood that the various slots, studs, guide rods and similar elements shown are not the only forms in which the controlling surfaces of the invention may be made, but that other specific relatively movable contacting surfaces could be employed for guiding purposes.

25 The invention in its broader aspects is not limited to the specific mechanisms shown and described but departures may be made therefrom within the scope of the accompanying claims without departing from the principles of the invention and without sacrificing its chief advantages.

30 What we claim is:

1. In a winding mechanism of the type mounted to swing away from a package spindle as the package builds up, a yarn delivery means, secondary guide means carrying said delivery means, primary guide means subjected to reciprocation of constant amplitude, a movable operative connection from said primary to said secondary guide, and a tertiary guide for said connection.

45 2. In a winding mechanism of the type mounted to swing away from a package spindle as the package builds up, a yarn delivery means, secondary guide means carrying said delivery means, primary guide means subjected to reciprocation of constant amplitude, a movable operative connection from said primary to said secondary guide, and means related to the amount of build-up of the package for altering the effective point of said connection.

50 3. In a winding mechanism of the type mounted to swing away from a package spindle as the package builds up, a roller adapted to bear against the package face, a yarn guide adjacent the line of contact of said roller and said face, and a movable finger carrying said yarn guide, a cam element fixed to said finger and constituting therewith a secondary guide, a trackway parallel to the package face whereon said secondary guide is constrained to move; a primary guide comprising a cam element and means for imparting longitudinal reciprocation of constant amplitude thereto, a trackway parallel to the package face whereon said primary guide is constrained to move, whereby the pathways of said two cam elements are parallel and adjacent but spaced apart; and tertiary guide means comprising an element connecting said two cam elements to drive the secondary from the primary, said connecting element being movable with respect to both, said tertiary guide means including

a trackway whereon said connecting element is constrained to move, and means for positioning said trackway at an inclination in either direction from the package face or parallel thereto, but always in a plane parallel to the paths of said two cam elements.

4. A winding mechanism of the type mounted to swing away from a package spindle as the package builds up, comprising in combination a frame including a generally vertical plate and a generally horizontal plate and a swinging arm carrying said frame, a bracket on said vertical plate, a horizontal yoke carried in said bracket and a roller supported by said yoke to bear against the package face, yieldable means urging said frame toward the package spindle, primary guide means movable on said frame comprising a finger upstanding adjacent said vertical plate and a cam element rigid with said finger overlying said horizontal plate, a trackway for said primary guide means parallel to the package face, means synchronized with the spindle drive for reciprocating said primary guide means through a constant distance; secondary guide means comprising a cam element and a yarn guide fixed thereto, a trackway parallel to the package face determining the direction but not the amplitude of movement of a yarn guide; and tertiary guide means affecting the amplitude but not the direction of movement of said yarn guide, said tertiary guide means comprising a trackway located between the paths of said cam elements, a runner thereon, rigid connections from said runner to each of said cam elements, each said connection being movable with respect to its respective cam element, and means for changing the inclination of said tertiary trackway with respect to the package face in accordance with the attained thickness of the package.

5. In a yarn winding guide mechanism of the type which swings away from the package as the package builds up, a primary guide reciprocating parallel to the package face through a constant distance, and including a cam slot inclined counterclockwise from a perpendicular to the line of movement; a secondary guide including a cam slot movable in a path parallel but variable in length with respect to that of the primary cam slot, a yarn guide carried by said secondary guide, and a connector between said slots movable with respect to each, a trackway whereon said connector moves, said trackway being of approximately the length of the primary guide path and inclinable upon its mid point with respect to said path, whereby according to the inclination of said trackway said connector causes the slots to intersect more or less closely to or remotely from the package face, thereby varying the length of travel of the secondary guide in comparison with the length of travel of the primary guide.

6. A yarn winding guide mechanism comprising guides with overlapping oppositely inclined cams, means for reciprocating one of said guides through a path of constant length, and means for reciprocating the other of said guides from the first-named guide in a parallel path, said means including a connector between said cams, and means for varying the points of application of said connector during each reciprocation.

7. A yarn winding guide mechanism comprising guides with overlapping oppositely inclined cams, means for reciprocating one of said guides through a path of constant length, and means for reciprocating the other of said guides from the first-named guide in a parallel path, said

means including a connector between said cams, means for varying the points of application of said connector during each reciprocation, and other means for altering the degree of such variation according to the progress of winding.

8. In a winding guide mechanism a plurality of interconnected guide elements movable in adjacent paths beneath and generally lengthwise of a cover, an absorbent pad attached to the underside of said cover in contact with some of said guide elements, and oil holes in said cover above said pad.

9. In a yarn winding machine, the combination of a pair of reciprocating cam plates having crossing slots, and means interconnecting said plates including a member having oppositely extending studs offset relatively to each other, each stud engaging in a slot.

10. In a yarn winding machine, the combination of a pair of reciprocating cam plates having crossing slots, and means interconnecting said plates including a member having oppositely extending studs offset relatively to each other, each stud engaging in a slot, and a pivoted guide rod on which said member is guided for reciprocation.

11. In a yarn winding machine, the combination of a pair of reciprocating cam plates having crossing slots, and means interconnecting said plates including a member having oppositely extending studs offset relatively to each other, each stud engaging in a slot, a guide for said member and means for varying the position of said guide to vary the relative movement of the plates.

12. In a yarn winding machine, the combination of a pair of reciprocating cam plates having crossing slots, and means interconnecting said plates including a member having oppositely extending studs, each stud engaging in a slot.

13. In a yarn winding machine, the combination of a pair of reciprocating cam plates having crossing slots, and means interconnecting said plates including a member having oppositely extending studs, each stud engaging in a slot, and a pivoted guide rod on which said member is guided for reciprocation.

14. In a yarn winding machine, the combination of a pair of reciprocating cam plates having crossing slots, and means interconnecting said plates including a member having oppositely extending studs, each stud engaging in a slot, a guide for said member and means for varying the position of said guide to vary the relative movement of the plates.

15. In a yarn winding machine, the combination of a reciprocating cam plate having an inclined slot, a guide member extending at an angle to the slot, a yarn guide, and means interconnecting the yarn guide and plate and including a slidably connector having a pin engageable in said slot and guided by the guide member.

16. In a winding machine of the type having a frame mounted to swing away from the package as the package builds up, a yarn guide, a primary guide means subjected to reciprocation of constant amplitude, a secondary guide carrying the yarn guide, means interconnecting the primary and secondary guides including an inclined slotted cam and pin, means for guiding the pin in a fixed path, and means for shifting the path to vary the reciprocation of the yarn guide as the package builds up.

17. In a winding machine of the type having a frame mounted to swing away from the package as the package builds up, a yarn guide, a primary guide means subjected to reciproca-

tion of constant amplitude, a secondary guide carrying the yarn guide, means interconnecting the primary and secondary guides including an inclined slotted cam and pin, a pivoted guide on which the pin is guided and means for pivotally moving the pin guide by swinging of the frame to reduce the travel of the yarn guide as the package builds up.

18. In a winding machine of the type having a frame mounted to swing away from the package 10 spindle as the package builds up, a yarn guide, a primary guide means subjected to reciprocation of constant amplitude, a secondary guide carrying the yarn guide, means interconnecting the primary and secondary guides including an in- 15

clined slotted cam and pin, means for guiding the pin in a fixed path, and means for maintaining a definite angular relation between the path and the surface of the package.

19. In a yarn winding machine, the combination of a pair of reciprocating cam plates having crossing slots, and means interconnecting said plates including a connector having oppositely extending pins, each pin engaging in a slot, a guide for said connector and means for holding the guide in a fixed angular position relatively to the surface of the package.

HOWARD E. SWIFT.
EDWARD R. DAVIS.
